[57] CLAIM

The ornamental design for an air treatment device enclosure, as shown.

DESCRIPTION

FIG. 1 is a top plan view of an air treatment device enclosure showing our new design;

FIG. 2 is a right side elevational view thereof;

FIG. 3 is a front elevational view thereof;

FIG. 4 is a rear elevational view thereof;

FIG. 5 is a left side elevational view thereof;

FIG. 6 is a bottom plan view thereof;

FIG. 7 is a view taken in the plane indicated by line 7—7 in FIG. 2, when the enclosure is open; and,

FIG. 8 is a perspective view showing our new design.
